CLAIM

The ornamental design for a motorcycle wheel, as shown and described.

DESCRIPTION

FIG. 1 is a close up view of the palm tree portion of the motorcycle wheel of FIG. 13, removed from the motorcycle wheel for ease of disclosure; invention, and

FIG. 2 is a left side head on view of the motorcycle wheel of FIG. 1.

FIG. 3 is a right side perspective view of the motorcycle wheel of FIG. 1.

FIG. 4 is a left side perspective view of the motorcycle wheel of FIG. 1.

FIG. 5 is a right side head on view of the motorcycle wheel of FIG. 1 with only the brake disc assembled.

FIG. 6 is a left side head on view of the motorcycle wheel of FIG. 1 with only the sprocket assembled.

FIG. 7 is a right side perspective view of the motorcycle wheel of FIG. 1 with the brake disc assembled.

FIG. 8 is a right side perspective view of the motorcycle wheel of FIG. 1 with the sprocket and brake disc assembled.

FIG. 9 is a left side perspective view of the motorcycle wheel of FIG. 1 with the sprocket and brake disc assembled.

FIG. 10 is a head on view of the brake disc of the motorcycle wheel of FIG. 1.

FIG. 11 is a head on view of the sprocket of the motorcycle wheel of FIG. 1.

FIG. 12 is an exploded view of the assembly of the motorcycle wheel of FIG. 1; and,

FIG. 13 is a close up view of the design of the motorcycle wheel of FIG. 1.
